UNITED STATES PATENT OFFICE

LAWRENCE K. LOFTIN, OF ALTAVISTA, VIRGINIA, ASSIGNOR TO THE LANE COMPANY, INC., A CORPORATION OF VIRGINIA

AROMA TIGHT LOCK

Application filed August 1, 1930. Serial No. 472,440.

While I have, merely for the purposes of illustration, shown my improved lock in connection with a chest, it will be understood that its use is not thus restricted.

5 Cedar chests are, if the manufacturers' instructions to keep the lid tightly closed followed, efficient, but the average person merely closes the lid down and neglects to lock it in such position, thereby defeating the purpose of the chest, because with the lid only partially closed the aroma from the inside of the chest will rapidly escape, thus reducing the efficiency of the chest.

10 The primary object of my invention is to provide a lock of such construction that the weight of the lid in the act of closing will be sufficient to operate the lock to securely and tightly hold the lid in closed position; and with this and other objects in view my invention consists of the parts and combination of parts hereinafter pointed out.

15 From experiments made with a large number of cedar chests, I have found that there is a leakage of aroma of cedar oil from chests through the key hole of the locks, which of course is objectionable, not only because of the escape of the aroma, but also because this escaping aroma attacks the exterior oils of 20 the exterior finish of the chests, and forms a gummy mass which spreads rapidly and not only mars the appearance of the chest, but discolors any textile material that may come in contact with such mass.

25 The primary object of my invention is to provide a lock for cedar chests of such construction to prevent the leakage of the aroma of cedar oil therethrough to the exterior of the chest.

30 A further object of my invention is to provide such a lock with a combined key and operating pin whereby the lock catch may automatically move to locking position and removed from such position by moving the said 35 combined pin, and with these and other objects in view my invention consists of the parts and combination of parts hereinafter pointed out.

In the drawings:—

Figure 1 is a front elevation of my im-

proved lock with the casing plate removed showing the lock in unlocked position.

Figure 2 is a vertical transverse section of Fig. 1 through the axis of the key stem, the key stem being shown in elevation.

55

Figure 3 is a view similar to Fig. 1 with the parts in locked position.

Figure 4 is a vertical transverse section through Fig. 3 with the key stem shown in elevation.

60

The reference numeral 1 designates the plate of the lock which has a flange 2 at its upper edge, provided with a catch hole 3. A casing 4 is attached to said plate and consists of a wall of the desired height, which wall is provided on one side with recesses or notches 5 and 6, and on the opposite side with stepped recesses or notches 7 and 8.

65

A pin 9 is secured to the plate 1 within the casing on which is fixedly secured a flat spring 10, the end portions 11 and 12 of which are deflected away from the plate 1. On this pin 9 and above the spring 10 is secured a coiled spring, the end 13 of which bears against the wall 4 of the casing, while the 75 other end 14 extends, substantially, transverse of the casing and terminates in the pin-like end 15, which extends at right angles to the plate 1.

70

The keeper 16 is provided with an opening 80 17 which is of greater diameter than, and is adapted to receive the pin 9, the said greater diameter permitting the keeper to be tilted bodily with reference to the post, for the purpose hereinafter pointed out. Keeper 16 is 85 provided with lugs 18, 19, 20 and 21 extending laterally therefrom, which lugs are, when the parts are assembled, seated in the recesses 5,

6, 7 and 8, respectively, the lugs 19 and 21 functioning as pivots for the keeper 16 on 90 which the keeper is tilted. The keeper 16 is provided with a lug or finger 22, which is in constant engagement with the end 12 of the

95 spring 10, whereby the keeper is maintained constantly in locking position. The combined key and keeper operating pin 23 is rigidly attached to the keeper and at its base the keeper is, preferably, dished to form a seat or pocket in which a coiled spring 24 is seated. The keeper is also provided with an

95

100

opening therethrough into which the pin 15 of the spring arm 14 projects. A latch opening 25 is formed through the keeper near its top edge.

Surmounting the keeper 16 is locking bolt 26 for the keeper, said bolt having notches or recesses 27 and 28 to receive the pin 15 of the spring arm 14. When the pin is in the notch 27 the bolt is in locked position, and when the pin is in notch 28, the bolt is in unlocked position. This bolt slides in notches formed in the edge of the casing wall 4 and is provided with a stop lug 29 that engages the casing wall when the bolt is in locked position. The bolt is provided in its lower edge with recesses 30 and 31 which are adapted to receive the lower end wall of the casing notch 6, the spring pin 15, when in notch 27, holding the notch 30 in engagement with said lower end wall and, when the pin 15 is in notch 28, the notch 31 is in engagement with said lower wall. An arm 32 extends from the lower edge of the bolt 26 and is provided with a finger 33 which finger normally does not engage the keeper, but when the lock 26 is moved to locked position the finger 33 slides beneath the keeper, thereby holding the keeper against tilting.

A key hole closure 34 of greater area than the key hole 35 of the lock is slidably mounted on the key pin 23 and is solely mounted on the spring 24, said closure slidably engaging the pin 36 which holds the closure against rotation on the key pin 23. A backing plate 37 closes the casing.

The keeper above and equal to the width of the latch hole 25 is provided with a depression 38, the bottom of which inclines toward the plate 1.

The latch is secured to the hinged top of the cedar chest and comprises a plate 39 and a depending latch 40 which has a lug 41 on one side thereof having a cam face which engages the depression 38 of the keeper, while the upper end of the lug 41 projects through the opening 25 of said keeper to hold the top of the chest in closed position.

The bolt 26 is provided with a locking arm 43 which extends upwardly above the bottom edge of the lug 18 of the keeper.

It is necessary, to maintain efficiency in a cedar chest, that the top be securely held in closed position; therefore the ordinary lock is not desirable because users will frequently be satisfied to merely close the lid which, due to many causes, will not form a tight closure with the top edges of the walls of the chest.

By the use of my improved lock, when the lid is moved to closed position, the latch 40 interlocks with the keeper 16 and holds the lid in intimate contact with the top edges of the walls of the chest.

Now assuming that the bolt 26 is in unlocked position with the spring pin 15 in

notch 28, and that the lid is closed, the keeper 16 may be detached from the latch 40 by pushing down upon and tilting the key pin 23, which in turn tilts the keeper 16 bodily on its pivot lugs 19 and 21, thus freeing the latch from engagement in the opening 25 of the keeper, whereupon the lid is free to be elevated.

With the lid closed and the latch in the opening 25 of the keeper, to lock the keeper against tilting, a key is mounted on the pin 23 and pushed into the lock carrying the closure 34 with it. On turning the key to the left it engages the bolt 26, pushes it to the left until its stop 29 contacts with the casing wall, and at the same time the arm 32 of the bolt is slid under the keeper. This movement of the bolt 26 causes its arm 43 to move into the path of the lug 18 of the keeper and thus acts as a further stop to prevent the tilting of the keeper. In this position the spring pin 36 is in the notch 27 of the bolt.

The closure 34 for the key hole is normally pressed by the spring 24 against the under face of the back plate 37 with an aroma tight joint.

I shall refer to the guard 34 as a valve in the claims.

What I claim is:—

1. In an aroma tight lock having a key hole opening through its casing, a movable keeper plate in said casing, a combined push and key stem secured to said keeper and projecting through said key hole, and a valve slidably mounted on said stem, means to hold normally the valve to seal said key hole.

2. In a key operated lock, a casing having a key hole, a tiltably mounted keeper, a combined key pin and push button secured to said keeper and registering with said key hole, a locking bolt in the casing movable to lock the keeper against movement, and a valve slidably mounted on said stem to seal the key hole.

3. In a key operated lock, a casing having a key hole, a tiltably mounted keeper within the casing, a combined key pin and push button secured to said keeper and registering with said hole, a locking bolt within the casing engaging opposite faces of the keeper when moved to locking position, and a valve slidably mounted on said stem within the casing, and means to yieldably hold the valve in sealed relation to said hole.

4. In an aroma tight lock having a key-hole in its casing, a keeper in the casing movable to locking and releasing positions, a combined key pin and push button for moving the keeper and registering with said keyhole, a locking bolt in the casing movable to lock the keeper against movement, and a valve mounted for movement to seal the keyhole when the key is removed.

5. In an aroma tight lock having a key-

- hole in its casing, a keeper in said casing movable to locking and releasing position, a combined key pin and push button for moving said keeper and registering with said keyhole, a key-actuated locking bolt in the casing movable to lock the keeper against movement, and a valve supported by said stem for movement to seal the keyhole when the key is removed.
6. In an aroma tight lock having a key-hole in its casing, a tiltably mounted keeper in said casing, a combined push and key stem for tilting said keeper, said stem registering with said keyhole, and a valve mounted on the stem and movable to seal the keyhole when the key is removed.
7. In an aroma tight lock having a key-hole in its casing, a tiltably mounted keeper in said casing, a combined push and key stem registering with the keyhole and operative for moving the keeper, a key-actuated locking bolt for locking the keeper against movement, and a valve mounted on the stem for movement to seal the keyhole when the key is removed.
8. In an aroma tight lock having a key-hole in its casing, a keeper in the casing movable to locking and releasing positions, a combined key-actuated and push stem for manipulating said keeper, and a key-actuated locking device for locking the keeper from movement.
9. In an aroma tight lock having a key-hole in its casing, a tilttable keeper plate in the casing movable to locking and releasing positions, a combined push and guide stem secured to the keeper and registering with the keyhole, and a sliding key-actuated locking bolt for locking the keeper against movement.
10. In an aroma tight lock having a keyhole in its casing, a movable keeper in the casing, a key-actuated and manipulating stem registering with the keyhole and connected to the keeper, a key-actuated locking device for locking the keeper from movement, the casing and keeper having opposed dished portions, a valve slidable on the stem and movable into the dished portion of the casing to seal the key opening when the key is removed, and a spring in the dished portion of the keeper engaging the valve for moving the same to sealing position.

In testimony whereof I affix my signature.
LAWRENCE K. LOFTIN.
